UNITED STATES PATENT OFFICE.

JOHN A. PRICE, OF SCRANTON, PENNSYLVANIA.

DESIGN FOR A STOVE-RAIL.

SPECIFICATION forming part of Design No. 17,101, dated February 8, 1867.

Application filed December 4, 1866. Serial No. 220,746. Term of patent 7 years.

To all whom it may concern:

Be it known that I, JOHN A. PRICE, of Scranton, in the county of Lackawanna and State of Pennsylvania, have invented and produced a new and original Design for Stoves, of which the following is a specification, reference being had to the accompanying drawings, forming a part thereof.

My design relates to rails for the side or ends of stoves, preferably cooking-stoves; and it consists of a rail of ogee or reversed curve shape, as shown in the accompanying drawings, in which—

Figure 1 is a perspective view showing a cooking-stove embodying my design, and Fig. 2 a sectional view of the rail detached.

This rail A is in the form of a frame, *a*, and provided with the open-work *b*, as shown, consisting of the curves and flowers, preferably of conventional form; or, if desired, it may be solid, with the ornamentation consisting of any suitable design or figures in relief or in-

taglio. At the corners of the rail are provided knobs or bosses *c*; or, if desired, these corners may be rounded.

25

1 claim—

1. The design for stove-rails, consisting of a rail of ogee form in cross-section, as shown.
2. The design for stove-rails, consisting of a rail of ogee form in cross-section and provided with the open-work, as shown.
3. The design for stove-rails, consisting of a rail of ogee form in cross-section, with the open-work *b*, and knobs *c* at the corners, as shown.
- 35 4. The design for stove-rails, consisting of a rectangular rail of ogee form in cross-section, with the open-work *b*, and knobs *c* at the corners, as shown.
